UNITED STATES PATENT OFFICE.

ADOLPH C. RECKER, OF OAKVILLE, CONNECTICUT, ASSIGNOR TO WATERBURY MANUFACTURING CO., OF WATERBURY, CONNECTICUT, A CORPORATION.

DESIGN FOR AN INVERTED GAS-BURNER.

42,808.

Specification for Design.

Patented July 16, 1912.

Application filed May 31, 1912. Serial No. 700,853. Term of patent 7 years.

To all whom it may concern:

Be it known that I, ADOLPH C. RECKER, a citizen of the United States, residing at Oakville, in the county of Litchfield and State of Connecticut, have invented a new, original, and ornamental Design for Inverted Gas-Burners; and I do hereby declare the accompanying drawing to be a full, clear, and exact illustration of the same, and which said drawing constitutes

part of this application and represents a perspective view of an inverted gas-burner embodying my design.

I claim:

The ornamental design for an inverted gas burner as shown.

ADOLPH C. RECKER.

Witnesses:

J. S. NEAGLE,
JOHN J. DONAHUE.
